UNITED STATES PATENT OFFICE.

ANTHONY SCHROEDER, OF CLEVELAND, OHIO, ASSIGNOR OF ONE-HALF TO JAMES MERLE FINNEY, OF CLEVELAND, OHIO.

METAL CONTAINER.

Application filed May 19, 1925. Serial No. 31,305.

This invention relates to a metal container, more particularly to the bung ring therefor and the method and means for interlocking the ring in position in the opening in one wall of the container to secure a permanent joint between the bung ring and the metal of the container wall.

Heretofore great difficulty has been experienced in positioning bung rings and providing between them and the container walls permanent joints or connections which would prevent the ring from getting loose due to the repeated screwing in and unscrewing of the bung plugs, with resulting leakages. To insure a permanent joint of this character as well as one that was liquid tight, different means and methods have been employed and resorted to, all necessitating extra expense and labor.

One object of my invention is to construct an improved bung ring and to provide an improved method and means for securing the ring in position in the opening therefor in the container wall in such manner that the ring will be interlocked with the metal and thus be permanently held in position in fixed relation to the wall of the container.

Another object of the invention is to provide an improved bung ring and a relatively simple connection therefor with the wall of the container, whereby the rings may be readily made and positioned.

Other objects of the invention will be apparent to those skilled in the art to which my invention relates from the following description taken in connection with the accompanying drawings, wherein—

Fig. 1 is a fragmentary side elevation of a container embodying my invention, parts being broken away.

Fig. 2 is a fragmentary section of the container before the bung ring is positioned in the opening therefor.

Fig. 3 is a plan view of the parts shown in Fig. 1.

Fig. 4 is a section on the line 4—4 of Fig. 3.

Fig. 5 is a section on the line 5—5 of Fig. 3.

Fig. 6 is a plan view of a bung ring embodying my invention and adapted for use in

connection with my process of interlocking 50 the ring with the metal of the container wall.

Fig. 7 is a section on the line 7—7 of Fig. 6.

Fig. 8 is a section on the line 8—8 of Fig. 6.

Fig. 9 is a side view of the ring, being taken on the line 9—9 of Fig. 6 looking in the direction of the arrows.

In the drawing, 1 indicates a container which may be formed in any suitable manner from sheet metal stock. The container comprises a body 2 and a head 3, the flanges 60 of these parts being seamed in any desired manner. For illustrative purposes, I have shown a container 1 having a head 2 that is flangeless or chimeless with a seam 4 between the flanges of the body and head of the container, this construction of container forming the subject matter of my co-pending application Serial No. 42,982, for which reason no claim is made herein to said container construction. 5 indicates an opening formed in one wall of the container, for example in the head 3. 6 indicates a bung ring adapted to be positioned in the opening 5 according to the method hereinafter set forth. 6^a indicates screw threads on the inner wall of 75 the ring to provide means to removably secure the plug (not shown) in the ring. The ring 6 is preferably drop forged, but may be of any other form of construction. If desired, in forming or shaping the ring 6, 80 I provide it with a body portion 7, to form a relatively wide seating base 7^a, and a neck 9. As shown, the side wall of the body portion 7 is provided with a plurality of substantially flat sides or faces 8, disposed at angles 85 to each other. The neck 9 is adapted to project through the opening 5, which is made to exactly fit the neck 9, with the metal of the wall surrounding the opening in engagement with the seating base 7^a of the body portion. 90 The neck 9 extends beyond the wall of the opening 5 to provide sufficient metal to permit it to be riveted over upon the wall of the head to secure the ring thereto. My invention consists in providing means for interlocking the metal of the bung ring 6 and the metal of the wall 3 surrounding the opening 5 so that danger of the ring getting loose

due to positioning of the plug (not shown) and removal thereof, is entirely overcome. These interlocking means comprise what may be termed lands 10 disposed upon the seating base 7^a, preferably at the corners formed by the angle faces 8 and adapted to be projected into the metal of the wall under the pressure required to rivet the neck 9 thereupon. While the lands 10 may be of any desired height, I prefer to make them of less height than the thickness of the wall 3, the purpose being to cause them to project into the metal of the wall against which the seating base 7^a fits without causing a bulging 15 of the wall 3 on its opposite surface, the metal of the wall being compressed by this action so that an interlocking relation will result between the wall and ring. This form of construction not only permits the rings to 20 be readily and economically manufactured, but also permits the riveting to be effected in a single operation by simple tools in an ordinary manner. By preference, the body portion of the ring is arranged on the inner 25 surface of the head 3 and its neck projects through the opening 5 to the outside of the free end of the neck is riveted over upon the upper surface of the head 3. In the manufacture of the rings I prefer to incline the seating base 7^a downwardly at an angle, toward the axis of the ring, from the side faces 8 thereof; thereby providing what may be termed a conical base or surface 7^a. As a result of this form of construction, the lands 10 30 are provided at the corners formed by the angle faces 8, since these points of the body portion are at a greater distance from the axis of the ring than the intermediate portions of the side faces. The rings may be drop-forged with the seating base 7^a inclined in the manner shown, or they may be otherwise made with flat seating bases and then the bases may be machined to the desired angle.

In forming the opening 5, I prefer to bend 45 the wall surrounding the opening downwardly, as shown in Fig. 2, so that the wall will fit against the seating base 7^a when the neck 9 of the bung ring 6 is fitted into the opening 5; this arrangement also facilitates the 50 riveting of the neck into its final position with the metal gripped between the seating base 7^a and riveted portion of the neck. As shown in Fig. 5, the lands 10 are pressed into the metal of the wall 3 and the latter 55 is clamped against the seating base at all points between the lands, due to the pressure applied in riveting the neck 9 over into final position, thus becoming interlocked therewith, as clearly shown in Figs. 1, 4 and 5. 60 In my construction, the lands 10 are uniformly spaced around the ring and being uniformly projected into the metal they act to prevent turning of the ring when a force is applied in a rotative direction to turn the plug.

65 In my form of construction the lands 10

are formed simultaneously with the forging of the ring and the interlocking relation between the lands 10 and wall of the head 3 is effected in connection with the riveting of the neck of the ring over on the metal. It will therefore be seen that in providing the interlocking means described and interlocking the ring and wall 3 together no extra cost or labor is involved. It will also be noted that my construction and method provide for 75 the permanent positioning of the bung ring without resort to welding or manipulation of the wall 3 and that one operation only is required to connect the ring in its receiving opening, that of riveting the neck 9. 80

To those skilled in the art to which my invention relates many changes in construction and widely differing embodiments and applications of the invention will suggest themselves without departing from the spirit and scope thereof. My disclosures and the description herein are purely illustrative and are not intended to be in any sense limiting. 85

What I claim is:

1. A bung ring comprising a neck and a 90 body portion forming a seating base and having flat side walls disposed at angles to each other and a land on said seating base at each corner formed by said side walls.

2. A bung ring comprising a body portion 95 forming a seating base and having flat side walls disposed at angles to each other and a neck, said seating base being inclined downwardly to provide lands at the corners of said side walls.

3. A metal container having an opening 100 formed in its wall in combination with a bung ring mounted in said opening, said ring comprising a polygonal body portion having a seating base shaped to provide lands on the base at the corners of said body portion and engaging one face of the wall surrounding the opening and a neck riveted over into engagement with the other face of the wall, said lands being of less height than the thickness 105 of said wall and adapted to be compressed into the metal thereof when the pressure for riveting is applied to said neck. 110

4. A metal container having an opening 115 formed in its wall in combination with a bung ring mounted in said opening, said ring comprising a body portion having a seating base fitting against one face of the wall surrounding the opening and a neck riveted over into engagement with the other face of the wall, said body portion having flat side faces disposed at angles to each other and the seating base thereof being inclined downwardly to leave at the corners of said side faces lands which are compressed into the metal of the wall when pressure for riveting the neck is applied thereto. 120

5. A bung ring comprising a body portion 125 having flat side walls disposed in angular relation and a neck, the upper face of the 130

body portion around the neck being of frusto- at angles to each other and lands on said conical shape circumferentially, whereby seating base at certain of the corners formed lands are formed on said upper face at the by said side walls.

10

corners of the ring.

In testimony whereof, I have hereunto sub-

6. A bung ring comprising a neck and a body portion forming a seating base and having substantially flat side walls disposed

ANTHONY SCHROEDER.
